Inventor
E. P. ELLIS.

UNITED STATES PATENT OFFICE.

ELIJAH P. ELLIS, OF OAK HALL, KANSAS.

FLOUR-BIN.

SPECIFICATION forming part of Letters Patent No. 406,038, dated July 2, 1889.

Application filed July 7, 1888. Serial No. 279,257. (No model.)

To all whom it may concern:

Be it known that I, ELIJAH P. ELLIS, a citizen of the United States, residing at Oak Hall, in the county of Clay and State of Kansas, have invented a new and useful Improvement 5 in Flour-Bin and Measuring Device, of which the following is a specification.

My invention relates to a flour-bin; and it consists in a certain novel construction and arrangement of devices, fully set forth hereinafter in connection with the accompanying drawings, and pointed out in the claim.

On the drawings, Figure 1 is a perspective view of the flour-bin embodying my improvements. Fig. 2 is a vertical central longitudinal sectional view thereof. Fig. 3 is a vertical central transverse sectional view of the same.

Referring to the drawings, A designates the rectangular vertically-elongated body of the device, in the upper portion of which is the flour-bin B, and in the lower portion the receiver C, which communicates with the bin, and is narrower than the same. The top of the bin is closed by the lid D, and its lower 25 end is separated from the upper end of the receiver by the screen E, above which is mounted the agitator F, having an operating-crank *on* its front end. The front side of the receiver is provided with the transparent 30 panel G, on opposite sides of which are arranged scales, which indicate, respectively, the amount of flour which the receiver contains either in pounds or quarts, whereby at any time during the operation of sifting the 35 operator can ascertain the amount sifted. The object in providing the scale of pints and quarts is that many recipes for cooking specify cupfuls instead of pounds, and a cupful usually represents one-half pint. The bottom 40 of the receiver is provided with the slide H,

which is adapted to be drawn out to allow the measured flour to be deposited in a suitable vessel.

As above mentioned, the receiver is narrower than the bin and does not occupy the 45 entire space between the sides of the body A, thereby forming compartments II, which may be provided with small canisters or boxes L, of any preferred shape. This construction, however, forms no part of my present invention. 50

This combined flour-bin and measuring device is designed to be hung on the wall above or adjacent to the table or stand, and to enable it to be suspended it is provided with 55 the apertured ears N N, adapted to be engaged with nails or hooks.

Having described my invention, I claim—

The herein-described flour-bin and measuring device, comprising the rectangular body 60 A, having its upper portion forming a flour-bin, the curved sieve and rotary stirrer mounted in said body at the bottom of the bin, and stationary receiver C, arranged beneath the sieve and secured to sides of the 65 said body at the base of the bin and having its bottom provided with a slide, said receiver being narrower than said body, and its sides being formed of vertical walls flaring at their upper ends, where they are secured 70 to the rectangular body, the transparent panel G in the side of said body, and the graduated scale, substantially as described. 75

In testimony that I claim the foregoing as my own I have hereto affixed my signature in presence of two witnesses.

ELIJAH P. ELLIS.
